UNITED STATES PATENT OFFICE.

HERMANN FINGERLE AND KARL KROUPA, OF NEW YORK, N. Y.

LOG-DYEING MACHINE.

1,239,429.

Specification of Letters Patent. Patented Sept. 4, 1917.

Application filed February 2, 1917. Serial No. 146,239.

To all whom it may concern:

Be it known that we, HERMANN FINGERLE and KARL KROUPA, subjects of the Emperor of Germany and the Emperor of Austria, respectively, and residing at New York, in the county of New York and State of New York, have invented certain new and useful Improvements in Log-Dyeing Machines, of which the following is a specification.

10 This invention relates to log dyeing machines and has for its object to provide simple and efficient means for forcing liquid dyes through entire logs, so as to dye the fibers thoroughly, at the same time driving 15 out the sap from the pores of the wood. A further object is to provide such means wherein a plurality of logs may be dyed simultaneously, even if the logs are of different diameters. A still further object is to 20 provide means whereby logs of irregular shape may be dyed, by the above described process, in their entire thickness, without waste of the irregular protrusions.

With the foregoing and other objects in 25 view, the invention consists in the particular construction, combination and arrangement of parts hereinafter described and shown in the accompanying drawing, in which:

Figure 1 is a partly sectional, partly elevational view of the device, showing two logs 30 in section and one in elevation inserted therein;

Fig. 2 is a plan view of the same, showing one half of the circle, the other half being 35 identical therewith, and partly broken away to show hidden parts;

Fig. 3 is a fragmentary plan view of a portion of the device, on an enlarged scale.

Like reference characters designate like 40 parts in the different views.

Referring more particularly to the drawing, 4 is a brick work base on which are mounted pedestals 5 supporting the base plate 6 of the machine, which is preferably 45 annular as indicated in the drawing. A similarly shaped top-plate 7 is supported overhead of the base plate 6, by threaded rods 8 and nuts 9, in an obvious manner. Nuts 10 are provided on the rods 8 over the 50 top plate 7 and, by turning these several nuts in the desired direction, the top plate 7 may be lowered or raised, as required.

Passages such as 11 are formed in the base plate 6 at several parts of its circumference, 55 extending nearly from one edge to the other edge of the ring, in a radial direction and

communicating by passages such as 12 with the surface of the ring intermediate the two extreme ends of the passages 11 and in that portion of the surface of the plate designed 60 as a seat for a log end. Pipes 13, secured into ports 14' provided in the bottom of the base plate 6, correspondingly to each, passage 11, lead to and support a centrally located tank or reservoir 14 and are provided 65 with valves 15 enabling each of the pipes 13 to be opened individually and independently from the others to communication with the tank 14 or to be shut off therefrom.

The logs 16, 17 and 18 are each placed on 70 the base plate 6, in positions corresponding to the passages 11, packing rings 19 being first inserted between the bottom of the logs and the top of the base plate. These rings 19 are preferably of rubber or similar resilient material and conform in shape and size to the circumference of the respective logs.

Similar packing rings 20 are inserted between the top of the logs and the bottom 80 of the top plate 7, whereupon the latter is forced downward, by turning the nuts 9 and 10, and thus air tight joints are formed between the two ends of the logs and the respective plates 6 and 7, leaving chambers 21 85 into which the passages 11 and 12 abut, and chambers 22 on top, from which passages such as 23, formed in the top plate 7, lead to the inner edges of the latter, under which is fastened a funnel shaped liquid collector 24.

The dye is forced into the reservoir 14, under pressure, through a pipe 25, then proceeds through the pipes 13, ports 14', passages 11 and 12, into the chambers 21 and 95 90 from there through the logs, driving the sap out before it and the latter, with the surplus dye, emerges on the top of the logs into the chambers 22 and from there, through the passages 23, into the collector 24, wherefrom it may be conveniently conducted to any desired place by means of a hose attachable to the outlet 26 of the collector.

When a log of smaller diameter than the distance between the extreme ends of the 105 passages 11 is desired to be dyed, as for instance shown by the log 17, as many of the ports of the passages 11 and 12 as may be left outside of the packing rings 19 will be plugged air tight, as at 27'. As shown in 110 Fig. 2, where the top plate is partly broken away, the packing rings 19 and 20 may

easily be shaped to conform to the irregular contours of the logs and thus permit to dye the logs all over, without losing the protruding portions.

5 To the outlet 26 of the liquid collector 24 is fastened a ring 27 having, integrally formed therewith, radial arms 28, with extensions 29 adjustably secured thereto. To the outer ends of the extensions 29 are pivotally secured the shackles 30, provided with hooks 31 at their respective outer ends. Chains 32 are hitched on the hooks 31 and encircle the logs so as to hold them securely in their respective positions between the top 10 and base plates.

Claims:

1. A log dyeing machine comprising, in combination, a base and a top plate adapted to hold therebetween a plurality of logs of 20 various diameters, standing vertically, packing rings to form air tight joints between the ends of the logs and the respective plates, said packing rings being adjustably conformable to the respective circumferences of 25 the ends of the logs, means to tighten the base and top plates together to hold the rings in compression, passages formed in the base plate for the admission of dyes and in the top plate for the outlet of the sap 30 and the surplus dye, means for forcing the dye into said first mentioned passages under pressure, and means for preventing the admission of dye to any one of said passages independently from the others.
2. A log dyeing machine comprising, in combination, a base plate, a top plate, a plurality of passages in said plates for the admission and outlet of liquid, respectively, rods and nuts adapted to support said top 40 plate over said base plate and to clamp said two plates together, a central reservoir having separate means of communication to each of said passages for the admission of liquid, each of said means of communication 45 being adapted to be opened or closed individually, irrespective of the others, said outlet passages all abutting into a common collector of liquid, and means connected to said liquid collector for supporting logs 50 clamped between said plates securely in position.

3. A log impregnating machine having upper and lower members provided with log end seats for respective engagement with the upper and lower ends of a vertically disposed interposed log, one of said members being movable toward and from the plane of the other and both being provided with liquid conveying passages having outlets at said seats, means for adjusting the movable member toward the other member to secure fluid tight joints between said seats and the extremities of an interposed log, and means for introducing fluid under pressure to the passages in the lower member to 65 upwardly traverse the grain of the log.

4. A log impregnating machine having upper and lower members provided with log end seats for respective engagement with the upper and lower ends of a vertically disposed interposed log, one of said members being movable toward and from the plane of the other and both being provided with liquid conveying passages having outlets at 70 said seats, means for adjusting the movable member toward the other member, adjustable means at the log end seats for defining the areas of exposures of said outlets to correspond with the diameters of the proximate log ends, and means for introducing fluid 75 under pressure to the passages in the lower member to upwardly traverse the grain of the log.

5. A log impregnating machine having upper and lower members provided with log end seats for respective engagement with the upper and lower ends of a vertically disposed interposed log, one of said members being movable toward and from the plane of the other and both being provided with 80 liquid conveying passages having outlets at said seats, means for adjusting the movable member toward the other member, adjustable means at the log end seats conformable in outline to the peripheries of the proximate log ends, to define the extent and shape 85 of the areas of exposure of said outlets, and means for introducing fluid under pressure to the passages in the lower member.

HERMANN FINGERLE.
KARL KROUPA.
